FLASHING BRICK OR TILE

George Fink, Yonkers, N. Y.

Application April 1, 1937, Serial No. 134,207

9 Claims. (Cl. 108—26)

My present invention relates to roofing material, and more particularly to an improved flashing brick, tile and/or coping for roofs and the like.

My invention is adapted to be incorporated in a parapet wall adjacent to the roof and to house the edges of the roofing material. When thus situated it extends preferably through the wall and the elements or units are arranged in overlapping relation along the length of the wall. The underlying portion of each wall element or unit is provided with a portion to receive and bind the overlapping portion of the adjacent element or unit, and each underlying portion is provided with a channel or seepage way which extends transversely of the element or unit—and also of the wall—and the construction is such that water finding its way into the channel or seepage way is conducted to the inside face of the wall and thence onto the roofing. The overlapping portion of the elements or units forms a cover or housing for the channel or seepage way in the adjacent element or unit.

The elements or units are ordinarily larger than the usual brick, being usually two bricks thick and two or more bricks wide, the width depending on the desired thickness of the wall. For appearance sake in the finished wall, the elements or units are grooved or scored to simulate ordinary building brick. The elements or units may be made of the usual brick clay, or other ceramic material, and burnt, as is usual, or may be made of any suitable, moldable, and preferably water proof material.

The elements or units may be made without the means for housing the edges of the roofing material if desired, and where it is desired to utilize the elements or units in the building of a parapet wall. When thus employed the elements or units are built into the wall at a point above the roof and act as a protecting dam to prevent seepage of water downwardly through the wall.

The present invention may also be embodied in a coping structure, in which event the shape, in end elevation, is similar to the usual coping block. Naturally the elements or units are wider than the wall structure and have incorporated therein the channel or seepage way to conduct water to the inside face of the parapet wall.

The principal object of my invention therefore, is an improved flashing brick or tile.

Another object is an improved flashing brick or tile for receiving and housing the edges of roofing material.

A further object of my invention is an im-

proved flashing brick or tile having incorporated therein transversely extending water seepage ways.

Other objects and novel features of the construction and arrangement of parts comprising the device will appear as the description of the invention progresses.

In the accompanying drawings:

Fig. 1 is a view, in perspective, of a parapet wall and roof structure showing a flashing brick or tile embodying my invention incorporated therein, and also showing a modified form of my invention.

Fig. 2 is a view, in perspective, of my improved flashing brick or tile.

Fig. 3 is a view, in perspective, of a through wall brick or tile embodying my invention.

Fig. 4 is an end view of a portion of a parapet wall, showing an element or unit, as illustrated in Fig. 3, incorporated therein.

Fig. 5 is a view, in perspective, of two flashing bricks or tile in operative relation to each other, the overlapping portion of one brick being broken away to illustrate the manner in which it cooperates with the underlying portion of the adjacent brick or tile.

Referring to the drawings, 10 designates a flashing brick or tile of my present invention, having a main body portion 11 extended at one end to form an underlying portion 12, and extending outwardly from the top thereof, in a direction opposite to the underlying portion 12 is an overlapping portion 13. Formed in the body 11 and underlying portion 12, and extending upwardly at an angle into the material of the body 11 and underlying portion 12 is a slot or groove 14, which may be supplied with a plurality of serrations 15 to assist in more firmly attaching the roofing material therein.

At the intersection of the body 11 and overlapping portion 13 is formed a groove or score 16 which gives to the element or unit the appearance of two bricks.

Formed integral with the overlapping portion 13 and underlying portion 12 is a rearward extension 16a, which provides an overhang which rests on the top of a brick or bricks forming part of a parapet wall when the element or unit is incorporated in such wall.

At the rear of the rearward extension 16a, coincident with the underlying portion 12, is a bevelled wall member 17, with its top edge lying in the same plane as the top surface of the overlapping portion 13. Attached to the end of the member 17 and extending along the end of the

rearwardly extending member 16a and underlying portion 12 is a bevelled wall member 18 which slopes downwardly to follow the bevelled upper surface 19 of the underlying portion 12, as shown. 5 The members 17 and 18, together with the adjacent end of the overlapping portion 13, form a receptacle on the top surface of the underlying portion 12 for the reception of cement or mortar, or other binding material to bind the underlying portion 12 to the overlapping portion 13 of the adjacent element or unit.

Intermediate the wall 18 and adjacent end of the overlapping portion 13 and extending from the wall member 17 to the visible face of the 15 underlying portion 12, is a raised rib 20. The space between the raised rib 20 and the adjacent end of the overlapping portion 13 constitutes a water seepage way which will conduct water transversely of the structure and down the visible 20 face of the underlying portion the wall member 17 preventing any water from flowing rearwardly of the structure, as shown in Fig. 2.

The structure above described and as illustrated in Fig. 2 may be built into the parapet 25 wall 21 shown in Fig. 1, where it will be noted that the elements or units are built into a course adjacent to the roof structure 22. In such Fig. 1, the edge of the roofing material 23 is positioned in the slot or groove 14, pitch, tar, or other suitable material being utilized to make a water 30 tight joint between the roofing material 23 and the elements or units. The serrations 15 materially assist in binding the roofing material in position.

35 It will be noted from an inspection of Fig. 1, that the elements or units extend throughout the width of the parapet wall 21 and therefore, any water that seeps downwardly through the wall 21 will encounter the course of elements or units and the water will find its way into the water seepage ways above described and will be led to the inside face of the wall 21 and thence onto the roof structure 22, from which it will flow to the usual gutters.

45 In Fig. 1, the ordinary brick under the rearward extensions 16a of the overlapping portions 13 and the underlying portions 12 is designated by the reference character 24. When built into the parapet wall 21, the elements or units of my present invention are indistinguishable from the 50 ordinary brick of the wall.

55 In Fig. 3 is illustrated a flashing brick or tile of my present invention adapted for use in constructing a parapet wall. In this figure, 26 designates the body of approximately two bricks thick and provided with the groove or score 27 to give the element or unit the appearance of two ordinary bricks. Formed integral with the body and extending outwardly therefrom is an overlapping portion 28, as shown. Also formed integral with the body 26 and extending outwardly therefrom in a direction opposite to the overlapping portion 28, is an underlying portion 30. On the top surface of the underlying portion 30 and at the rear thereof, as shown in Fig. 3, is a bevelled upstanding wall 31. Attached to the wall 31 and located at the end face of the underlying portions 30, is a wall 32. On the upper face of the underlying portion 30 is a raised rib 33 which lies parallel to but spaced apart from the wall 32 and adjacent face of the element or unit 26. There is thus formed on the upper face of the underlying portion 30 a water seepage channel or way 34, and a cement receiving channel 35.

70 The manner in which a plurality of elements

or units 26 are built into a wall, as the wall 36 illustrated in Fig. 4, is shown clearly in Fig. 5, and is also illustrated in Fig. 1. The end of an element or unit is positioned adjacent and parallel to the end of the underlying portion 30 of 5 an adjacent unit, being united thereto by cement, mortar or other binder, with the overlapping portion of the first said unit resting on top of the walls 31 and 32, and raised rib 33, formed on the upper surface of the underlying portion 30 10 of the adjacent unit, the end of the overlapping portion 28 of the first said unit lying parallel to and adjacent the end of the body 26 of the adjacent element or unit, and being united thereto by cement, mortar, or other suitable binder. 15

It will be understood that the channel 35 is filled with mortar or cement, as are also the spaces between the body 26 and ends of the underlying portion 30 and overlapping portion 28 20 of adjoining blocks in the same course. 20

Ordinarily the elements or units shown in Figs. 3, 4 and 5 are built as wide as the wall 36, but where the wall 36 is extra wide, if desired, the elements or units may be built with a step 39, as shown in Fig. 4, to permit bricks of the usual 25 type to appear on the outside face of the wall.

Where my invention is embodied in a coping, it will be similar to the forms shown in Figs. 3 and 5, but the grooves or scores 27 may be omitted and the top surface of the body 26 and integral overlapping portion 28 may be bevelled laterally outward from the longitudinal ridge. 30

While I have described the preferred embodiments of my invention in detail, it is to be understood that the showing is illustrative only, and 35 I am not to be limited, other than as pointed out in the appended claims.

I claim:

1. An improved flashing brick comprising, a body, an overlapping member extending outwardly therefrom at one end thereof, an underlying member extending outwardly therefrom at the opposite end, and a water seepage way formed on the upper surface of the underlying member. 40

2. An improved flashing brick comprising, a 45 body, an overlapping member extending outwardly therefrom at one end thereof, an underlying member extending outwardly therefrom at the opposite end, and a seepage way formed on the upper surface of the underlying member and 50 extending transversely of the body.

3. An improved flashing brick comprising, a body, an overlapping member extending outwardly therefrom at one end thereof, an underlying member extending outwardly therefrom at the opposite end, a water seepage way formed on the upper surface of the underlying member, and extending transversely of the body, and a 55 dam at one side of the underlying member for preventing movement of water in the water 60 seepage way onto said side.

4. An improved flashing brick comprising, a body, an overlapping member extending outwardly therefrom at one end thereof, an underlying member extending outwardly therefrom at the opposite end, a dam at one side of the underlying member, a dam at the end of the underlying member remote from the body and of less height than the first said dam, and a dam on the upper surface of the underlying member 65 spaced from the second said dam and the adjacent end of the body dividing the upper surface of the underlying member into a bonding material receiving bed and a water seepage way extending transversely of the underlying member. 70

75

5. An improved flashing brick comprising, a body, an overlapping member extending outwardly therefrom at one end thereof, an underlying member extending outwardly therefrom at 5 the opposite end, a dam at one side of the underlying member, a dam at the end of the underlying member remote from the body and of less height than the first said dam, a dam on the upper surface of the underlying member spaced 10 from the second said dam and the adjacent end of the body and dividing the upper surface of the underlying member into a bonding material receiving bed and a water seepage way extending transversely of the underlying member, and a 15 roofing material receiving recess formed in the body and underlying member.
6. An improved flashing brick comprising, a body, an overlapping member extending outwardly therefrom at one end thereof, an underlying member extending outwardly therefrom at 20 the opposite end, a dam at one side of the underlying member, a dam at the end of the underlying member remote from the body and of less height than the first said dam, a dam on the upper surface of the underlying member spaced 25 from the second said dam and the adjacent end of the body and dividing the upper surface of the underlying member into a bonding material receiving bed and a water seepage way extending 30 transversely of the underlying member, and a roofing material receiving recess formed in the body and underlying member and extending upwardly and inwardly of the said body and underlying member from the lower edges thereof.
- 35 7. An improved flashing brick comprising, a body of substantially twice the height of an ordinary brick, a dividing groove formed therein to simulate the bond between two superposed bricks and dividing the body into an upper and lower 40 part, an overlying member formed integral with

the upper part of the body and extending outwardly from one end thereof, an underlying member formed integral with the lower part of the body and at the end thereof remote from the overlying member, and a water seepage way 5 formed on the upper surface of the underlying member and extending transversely thereof.

8. An improved flashing brick comprising, a body of substantially twice the height of an ordinary brick, a dividing groove formed therein to 10 simulate the bond between two superposed bricks and dividing the body into an upper and a lower part, an overlying member formed integral with the upper part of the body and extending outwardly from one end thereof, an underlying 15 member formed integral with the lower part of the body and at the end thereof remote from the overlying member, a water seepage way formed on the upper surface of the underlying member and extending transversely thereof, and means 20 for permitting flow of water in said seepage way in one direction only.

9. An improved flashing brick comprising, a body of substantially twice the height of an ordinary brick, a dividing groove formed therein to 25 simulate the bond between two superposed bricks and dividing the body into an upper and a lower part, an overlying member formed integral with the upper part of the body and extending outwardly from one end thereof, an underlying 30 member formed integral with the lower part of the body and at the end thereof remote from the overlying member, a water seepage way formed on the upper surface of the underlying member and extending transversely thereof, means for 35 permitting flow of water in said seepage way in one direction only, and a top for said seepage way formed of the overlying member of the next adjacent flashing brick.

GEORGE FINK. 40
